Howard C. Thompson
ATTORNEY

UNITED STATES PATENT OFFICE.

DOMENICO GUARINO, OF NEW YORK, N. Y.

TROWEL.

Application filed January 22, 1927. Serial No. 162,885.

This invention relates to trowels and particularly to devices of this class for forming mortises, molding and the like on the walls and ceilings of rooms and compartments; and the object of the invention is to provide a tool of the class specified with a blade provided with a double edge to permit of its use from left to right and right to left on walls arranged at angles to each other to facilitate the formation of cornices or molding and the miter intersections thereof where the walls join in a corner; a further object being to provide a tool of the class specified, the blade edges of which are arranged at an angle to each other for example, at an angle of ninety degrees to each other, and preferably forty-five degrees with reference to the guide square edge of the tool, whereby in the forming of cornices and moldings, a blade surface will extend at forty-five degrees from the corner portion of adjacent walls; and with these and other objects in view, the invention consists in a tool of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a diagrammatic view, illustrating the use of my improved tool, the tool being shown in full lines and indicated in dotted lines in another position.

Fig. 2 is a section on the line 2—2 of Fig. 1; and,

Fig. 3 is a view looking in the direction of the arrow 3, Fig. 1, and on an enlarged scale.

The tool, in the construction shown, comprises a body or frame 5 which may be constructed of any suitable material and in any desired manner. In the construction shown, the frame consists of blade supporting portions 6—7 arranged at right angles to each other forming a V-shaped body to the outer faces of which, blades 8 are adapted to be detachably supported. The edges 9 of the blades are of similar contour to form a predetermined cornice or molding on the walls and ceiling of a room or compartment, it being understood that said contour may be

modified and changed to suit the particular requirements, or the desired design of the cornice or molding.

Extending from one corner portion of the frame or the body parts 6 and 7 thereof, is a square edge and tool guiding member 10, provided with bearing faces 11 and 12, arranged at right angles to each other and corresponding to the arrangement of the blade supporting portions 6—7 as clearly seen in Fig. 3 of the drawing, it being understood, however, that said portions 6 and 7 are arranged at forty-five degrees with reference to the longitudinal plane of the bearing faces 11 and 12.

A handle member 13 extends from the outer end of the member 10 to the outer end of the blade portions 6 and 7 as clearly seen in Fig. 1 of the drawing, and said handle member is also arranged at forty-five degrees with reference to the longitudinal plane of the member 10. In other words, the frame consists of a triangular body comprising the blade supporting portions 6—7, the member 10 and handle member 13.

In the use of my improved tool and forming a cornice, molding or the like on two walls 14 and 15, meeting at the corner 16 as seen in Fig. 1 of the drawing, for example, the usual guide strips 17 are secured to the walls, and in moving the tool from left to right along the wall 14, the face 12 of the member 10 rests upon the strip 17, and the face 11 bears upon the wall 14 as seen in Fig. 2 of the drawing, producing a right angle guide for the tool in its movement over the wall and in forming a cornice at the ceiling 18 as indicated in Fig. 2 of the drawing. The upper edge of the tool is guided along the ceiling surface; thus, in the right to left hand movement of the tool, along the wall 15, the bearing face 11 rests upon the strip 17, and the bearing face 12 upon the wall as indicated in the dotted line position of the tool, in Fig. 1 of the drawing.

In both movements of the tool, it will be apparent that when the tool reaches the corner 16 of the walls 14—15, the face of the blades 8 and of the blade supporting portions 6—7 will be arranged at forty-five degrees to the corner 16, thus producing a perfect miter. The angular arrangement of the blades 8 with reference to the guide member 10, in forming the true mortise, constitutes one of the distinctive features of my invention.

It will be understood that my invention is not necessarily limited to the particular contour of the edges 9 of the blades 8, nor is my invention limited to the specific angular arrangement of the blades 8 with reference to each other and also the blade supporting portions 6 and 7, and still further, my invention is not necessarily limited to the specific form and construction of the frame 10 herein shown and described, and various changes in and modifications of the construction herein set out may be made within the scope of the appended claims, without departing from the spirit of my invention 15 or sacrificing its advantages.

Having fully described my invention, what I claim as new and desire to secure by Letters Patent, is:—

1. A tool of the class described, comprising 20 a body portion having two blade edges of similar contour arranged on opposite sides of said body portion, said blade edges being angularly disposed with reference to each other and intersecting in surfaces 25 arranged at right angles to each other forming corner portions disposed in opposite relation on said body portion, and a straight edge and guide member extending from one corner portion of the tool at an angle of 30 forty-five degrees with reference thereto.

2. A tool of the class described comprising 35 a body portion having two blade edges of similar contour arranged on opposite sides of said body portion, said blade edges being angularly disposed with reference to each other and intersecting in surfaces arranged at right angles to each other forming corner portions disposed in opposite relation on said body portion, a straight edge 40 and guide member extending from one corner portion of the tool at an angle of forty-five degrees with reference thereto, and a handle member extending from the other corner portion of the tool to the end portion 45 of said first named member.

3. A tool of the class described, comprising 50 a body portion having two blade edges of similar contour arranged on opposite sides of said body portion, said blade edges being angularly disposed with reference to each other and intersecting in surfaces arranged at right angles to each other forming corner portions disposed in opposite relation on said body portion, a straight edge and guide 55 member extending from one corner portion of the tool at an angle of forty-five degrees with reference thereto, a handle member extending from the other corner portion of the tool to the end portion of said first 60 named member, and said first named member having bearing faces arranged at right angles to each other.

4. In a tool of the class described, a frame 65 comprising blade supporting portions arranged angularly with reference to each

other, a square edge and guide member arranged at forty-five degrees with reference to said blade supporting portions, and a handle member arranged at right angles to the blade supporting portions and coupled 70 with the free end of said first named member.

5. In a tool of the class described, a frame comprising blade supporting portions arranged angularly with reference to each other, a square edge and guide member 75 arranged at forty-five degrees with reference to said blade supporting portions, a handle member arranged at right angles to the blade supporting portions and coupled with the free end of said first named member, and 80 said blade supporting portions being arranged at right angles to each other.

6. In a tool of the class described, a frame comprising blade supporting portions arranged angularly with reference to each other, a square edge and guide member 85 arranged at forty-five degrees with reference to said blade supporting portions, a handle member arranged at right angles to the blade supporting portions and coupled with the free end of said first named member, said 90 blade supporting portions being arranged at right angles to each other, and blades adapted to be detachably coupled with said blade supporting portions. 95

7. In a tool of the class described, a frame comprising blade supporting portions arranged angularly with reference to each other, a square edge and guide member arranged at forty-five degrees with reference 100 to said blade supporting portions, a handle member arranged at right angles to the blade supporting portions and coupled with the free end of said first named member, said blade supporting portions being arranged at right angles to each other, and blades adapted to be detachably coupled with said blade supporting portions, said blades having peripheral edges of similar contour. 105

8. A tool of the class described comprising 110 a body portion provided at one end with a V-shaped blade supporting member consisting of laterally extending parts, the faces of which are offset and arranged at substantially ninety degrees to each other, each of said parts having blade edges of 115 similar contour, and a handle member extending from the intersection of said parts and arranged at an angle thereto.

9. A tool of the class described comprising 120 a body portion provided at one end with a V-shaped blade supporting member consisting of laterally extending parts, the faces of which are offset and arranged at substantially ninety degrees to each other, each of said parts having blade edges of similar contour, a handle member extending from the intersection of said parts and arranged at an angle thereto, and a straight edge and guide member extending from one corner 125 130

portion of the intersection of said parts in the direction of and supported at its outer end by said handle member.

10. A tool of the class described comprising a substantially triangular body portion consisting of a blade supporting member, a handle member, and a straight edge and guide member, said blade supporting member being arranged at one end and bridging said last named members and consisting of laterally extending parts, the outer faces of which are opposed, and the contour of the blade supported on one of said parts being similar to the contour of the blade on the other part, and said blades intersecting at their ends in edges disposed at right angles to each other, 30
15 said blades being arranged at right angles to each other and in alinement with the intersecting edges of said blades.
11. A tool of the class described comprising a substantially triangular body portion consisting of a blade supporting member, a handle member, and a straight edge and guide member, said blade supporting member being arranged at one end and bridging said last named members and consisting of 35
20 laterally extending parts, the outer faces of which are opposed, the contour of the blade supported on one of said parts being similar to the contour of the blade on the other part, and said blades intersecting at their ends in edges disposed at right angles to each other.
- 25

to the contour of the blade on the other part, and said blades intersecting at their ends in edges disposed at right angles to each other, 30
35 and said straight edge and guide member having bearing faces arranged at right angles to each other and in alinement with the intersecting edges of said blades.

12. A tool of the class described comprising a body portion provided at one end with a V-shaped blade supporting member consisting of laterally extending parts, the faces of which are offset and arranged at substantially ninety degrees to each other, each of said parts having blade edges of similar contour, a handle member extending from the intersection of said parts and arranged at an angle thereto, and a straight edge and guide member extending from one corner portion 40
45 of the intersection of said parts in the direction of and supported at its outer end by said handle member, and said straight edge and guide member having bearing faces arranged at right angles to each other. 50

In testimony that I claim the foregoing as my invention I have signed my name this 17th day of January 1927.

DOMENICO GUARINO.
